UNITED STATES PATENT OFFICE.

THOMAS E. ADAMS, OF PINE BLUFF, ARKANSAS, ASSIGNEE OF ONE-HALF
TO CHARLES H. SEABROOK, OF PINE BLUFF, ARKANSAS.

ENGINE-TRUCK.

No. 830,274.

Specification of Letters Patent.

Patented Sept. 4, 1906.

Application filed April 7, 1906. Serial No. 310,435.

To all whom it may concern:

Be it known that I, THOMAS E. ADAMS, a citizen of the United States, residing at Pine Bluff, Arkansas, have invented a certain new and useful Improvement in Engine-Trucks, of which the following is a full, clear, and exact description, such as will enable others skilled in the art to which it appertains to make and use the same, reference being had to the accompanying drawings, forming part of this specification, in which—

Figure 1 is a plan view of a swinging center-bearing engine-truck embodying the features of my invention. Fig. 2 is a side elevation thereof. Fig. 3 is an enlarged view taken on approximately the line 3 3 of Fig. 1. Fig. 4 is a detail view taken on the line 4 4 of Fig. 3. Fig. 5 is a plan view of a rigid center-bearing engine-truck embodying the features of my invention, and Fig. 6 is a side elevation of the truck shown in Fig. 5.

This invention relates to engine-trucks; and one object of my invention is to provide a cast-steel engine-truck that can be manufactured at a much lower cost than the trucks heretofore in use and which will be more rigid and last much longer than said trucks.

In the truck herein shown, which represents the preferred embodiment of my invention, the pedestals and also the spring-seats are cast integral with the side frames of the truck. The side frames are provided on their upper faces with integral lugs between which the center-bearing frame is confined, and said center-bearing frame is provided with integral flanges that engage the inner faces of the side frames of the truck and are connected thereto by rivets or pins, the ends of the center-bearing frame being also connected to the upper faces of the side frames by suitable fastening devices. The center-bearing frame, whether it be for a rigid center-bearing or a swing center-bearing, is formed in one piece, and as it is confined between the integral lugs on the side frames of the truck and is provided with depending flanges which engage the inner faces of said side frames it will be impossible for said frames and the pedestals to spring inwardly, as was often the case with the trucks heretofore in use. Furthermore, the lugs on the side frames between which

the center-bearing frame is confined remove the strain from the connecting-rivets and prevent the same from being sheared off or loosened.

By forming the pedestals and spring-seats integral with the side frames there is no possibility of said parts working loose, and the cost of manufacturing the same is reduced greatly, due to the fact that no machining or planing down of coöperative parts is necessary, as would be required if the pedestals and spring-seats were formed separate from the side frames.

Referring to the drawings, 1 designates the side frames of a truck, having spring-seats 2 and pedestals 3 of substantially channel shape formed integral therewith. Lugs 4 are formed on the upper faces of the rails of the side frames, and a one-piece center-bearing frame 5 is confined between said lugs, said center-bearing frame being provided with depending flanges 6, which engage the inner faces of the rails of the side frames 1 and are connected thereto by rivets 7. The end portions of the center-bearing frame comprise continuous pieces 8, which rest on the upper faces of the rails of the side frames and are connected thereto by rivets 9, so that it is impossible for the side frames to spring inwardly, and there is no liability of the connecting-rivets being sheared off or loosened, as the lugs 4 relieve the same from the strains due to starting and stopping. Bars 10 are connected to the lower ends of the pedestals 85 of each side frame by bolts 11, and these bars are braced by cross-pieces 12, to which they are connected by bolts 13.

In Figs. 1, 2, and 3 I have shown the form of center-bearing frame which I prefer to use for a swing center-bearing, and in this form the cross members 14, which are formed integral with the continuous pieces 8 of the frame, are provided with steel bushings 15, that receive the pins 16, which are employed for carrying the swinging hangers 17, to which the center-bearing casting 18 is connected. By providing the center-bearing frame with steel bushings to receive the pins 16 the bushings can be replaced by new ones when they become worn, and thus obviate the necessity of using an entire new center-bearing frame.

2
Preferably I provide the center-bearing frame with ribs 19, which act as an additional strengthening means.

In Figs. 5 and 6 I have shown an engine-truck having a rigid center-bearing, the center-bearing casting 18' being provided with continuous end pieces 8' and with flanges 6', which are connected to the rails of the side frames 1 in the same manner as described for connecting the center-bearing frame and side frames in the form shown in Figs. 1, 2, and 3.

Having thus described the invention, what is claimed as new, and desired to be secured by Letters Patent, is—

1. An engine-truck consisting of cast-steel side frames provided with integral pedestals, the top members of said side frames being formed straight and each being provided with a pair of upwardly-projecting lugs, a cast center-bearing frame resting on the upper faces of the top members of the side frames and being provided with depending flanges which contact with the inner faces of said top members and fastening devices passing

through the end portions of the center-bearing frame and the top members of the side frames; substantially as described. 25

2. An engine-truck having side frames, a frame for a swinging center-bearing consisting of continuous end members which rest on the upper edges of the side frames, cross members formed integral with said continuous end members, flanges depending from said end members, and contacting with the inner faces of the side frames, lugs carried by 30 said side frames and engaging the ends of said continuous end members, and fastening devices connecting said end members and their depending flanges to the side frames; substantially as described. 35

In testimony whereof I hereunto affix my signature, in the presence of two witnesses, this 5th day of April, 1906.

40
THOMAS E. ADAMS.
